(57) **CLAIM**

The ornamental design for a cap for injection pen, as shown and described.

DESCRIPTION

FIG. 1 is a top perspective view of a first embodiment of a cap for an injector pen embodying our new design; FIG. 2 is a bottom perspective view of the cap for the injector pen shown in FIG. 1;

FIG. 3 is a side view of the cap for the injector pen shown in FIGS. 1 and 2;

FIG. 4 is a top view of the cap for the injector pen shown in FIGS. 1-3;

FIG. 5 is a front view of the cap for the injector pen shown in FIGS. 1-4;

FIG. 6 is a rear view of the cap for the injector pen shown in FIGS. 1-5;

FIG. 7 is an opposite side view of the cap for the injector pen shown in FIGS. 1-6;

FIG. 8 is a bottom view of the cap for the injector pen shown in FIGS. 1-7;

FIG. 9 is a top perspective view of a second embodiment of a cap for an injector pen embodying our new design;

FIG. 10 is a bottom perspective view of the cap for the injector pen shown in FIG. 9;

FIG. 11 is a side view of the cap for the injector pen shown in FIGS. 9 and 10;

FIG. 12 is a top view of the cap for the injector pen shown in FIGS. 9-11;

FIG. 13 is a front view of the cap for the injector pen shown in FIGS. 9-12;

FIG. 14 is a rear view of the cap for the injector pen shown in FIGS. 9-13;

FIG. 15 is an opposite side view of the cap for the injector pen shown in FIGS. 9-14; and,

FIG. 16 is a bottom view of the cap for the injector pen shown in FIGS. 9-15.

(Continued)

The ornamental design that is claimed is shown in solid lines in the drawings. The broken lines in the drawings represent portions of a cap for an injector pen that form no part of the claimed design.
